THERMOSTATIC ELEMENT

Norman L. Derby, New York, N. Y.

Application November 1, 1930, Serial No. 492,707

13 Claims. (Cl. 297—15)

This invention relates to thermostatic elements.

An object of this invention is to furnish an improved thermostatic element that will contract and expand longitudinally in response to a change 5 in temperature.

Another object of this invention is to furnish automatic devices utilizing a thermostatic element that will expand or contract in a generally longitudinal direction in response to a change in 10 temperature.

Another object is to furnish an improved thermostatic element with alternate portions having relatively high electric conductivity while the remaining portions have a relatively low electric 15 conductivity.

Another object of this invention is to furnish a thermostatic element in which one of the metals is continuous while the other metal is divided.

Another object of this invention is to furnish 20 an improved corrugated thermostatic element.

Of the drawings.

Fig. 1 is a perspective view of a sheet of bimetallic stock from which the thermostatic element is made.

Fig. 2 is a perspective view of a thermostatic element made from the stock of Fig. 1.

Fig. 3 is an elevation in section on the line 3—3 of Fig. 3—A, of a quick opening and closing switch included in an electric heating circuit and utilizing 30 the new type of thermostatic element.

Fig. 3—A is an end view of the switch shown in Fig. 3.

Fig. 3—B is an end elevation of the switch with the thermostatic element in section on the line 35 3B—3B of Fig. 3.

Fig. 4 is a perspective view of a sheet of thermostatic stock differing slightly in construction from that shown in Fig. 1, in that the invar connecting sections are wider.

Fig. 4—A is a view similar to Fig. 4 showing a slightly different construction of thermostatic stock with sections of the upper and lower layers removed.

Fig. 5 is a perspective view showing another variation in form of the thermostatic stock.

Fig. 6 and Fig. 7 are perspective views illustrating the formation of sheet stock by rolling down a compound ingot.

Fig. 8 is a perspective view of the thermostatic element comprising two side by side corrugated strip sections.

Fig. 9 is a perspective view of a tube constructed of bi-metallic sheet stock with a longitudinal 55 welded joint.

Fig. 10 is a sectional view of a deeply corrugated tube made from the tubing of Fig. 9.

Fig. 11 is a perspective view of a bimetallic tube comprising three superposed tubes joined permanently together.

Fig. 12 is a sectional view of a deeply corrugated tube constructed of the tubing of Fig. 11 having sections of its inner and outer surfaces removed to make the tubing expand and contract in response to a change in temperature.

Fig. 13 is a perspective view of another type of thermostatic tubing, the walls of which will expand or collapse in response to a change in temperature.

Fig. 14 is a sectional view of the tubing shown in Fig. 13 illustrating the manner in which the tube collapses when heated.

Fig. 15 is a perspective view of a corrugated thermostatic element having portions curved transversely to the corrugation curves thereof 20 to stiffen the element.

Fig. 16 is a plan view and Fig. 17 is an end view of sections of a sheet of thermostatic stock similar to that shown in Fig. 1 and Fig. 7.

Fig. 18 is a section on the line 18—18 of Fig. 16, 25 of a corrugated strip shown flat in Fig. 16.

Fig. 19 is an enlarged front view of a portion of the strip shown in Fig. 18 after said strip has been deeply corrugated.

Fig. 20 is an end view of the strip shown in 30 Fig. 19.

Fig. 21 is a front view of a corrugated strip shown flat in Fig. 16 in which the corrugation grooves are of helical form.

Fig. 22 is an end view of the strip shown in 35 Fig. 19.

The usual type of commercial bimetallic element consists of two continuous strips of metal having widely differing coefficients of heat expansion, usually brass and invar steel joined 40 permanently together face to face. This type of element when corrugated and heated will not expand longitudinally, but rather, will tend to coil into a circular form. The element which is the subject of this invention will expand or contract longitudinally in response to a change of temperature.

Referring to the drawings, Fig. 1 shows a sheet of this new type of bimetallic thermostatic stock. Each surface shows alternate sections of the two metals, the metal having a low coefficient of heat expansion being invar steel and the metal having a high coefficient of heat expansion being lead free brass. It will be noticed that sections of the sheet showing brass on the upper surface 55

will show invar on the under surface and likewise sections showing invar steel on the upper surface will show brass on the under surface. In the particular sheet of stock shown in Fig. 1 strips of brass are permanently joined to a continuous sheet of invar steel. In Fig. 2 the sheet of stock Fig. 1 has been corrugated so that the brass sections come on the inside and the invar on the outside of the bends of the corrugations, and the seams are located on the sides of the corrugations half way between the lower and upper bends. The corrugated thermostatic element shown in Fig. 2 will expand longitudinally, or parallel to its length, when heated. However if the sheet of stock shown in Fig. 1 is corrugated so that the brass is on the outside of the bends and the invar on the inside of the bends the element will contract longitudinally instead of expanding when heated.

20 The preferred method of making the compound stock from which the corrugated thermostatic element is formed comprises forming a compound ingot as shown in Fig. 6 approximately 12" wide x 36" long x $\frac{3}{4}$ " thick consisting of a slab of invar steel having longitudinal grooves which are filled with brass, the brass being permanently joined to the walls of the grooves. The brass is preferably fused into the grooves by automatic arc welding. After the compound ingot is formed it is reduced in thickness, to say $\frac{1}{8}$ " by cold rolling in the direction of its length as shown in Fig. 6. Then the reduced ingot is sheared into slabs, the first slab being sheared off on line A—B. This slab is then reduced to the finished thickness by 35 rolling in the opposite direction, that is, at right angles to the first rolling operation. The second rolling operation is shown in Fig. 7.

After the last rolling operation the bi-metallic stock strip may be given the corrugated form 40 shown in Fig. 2, by several sets of corrugating rolls, each succeeding set imparting deeper and narrower corrugations to the sheet of stock. Instead of corrugating rolls, a die similar to that used for making corrugated metal roofing may be 45 used to corrugate the strip.

As is well known, the reduction by cold rolling imparts a grain to metal and the maximum strength is obtained by bending the metal at right angles to the grain. In the operation shown 50 in Fig. 6 the grain formed is parallel to the length of the slab and in the operation shown in Fig. 7 the grain formed is in the transverse direction. When a corrugated thermostatic element is formed from the finished stock of Fig. 7, the 55 bends will be at right angles to the grain and give the element maximum strength to resist bending strains.

There are several other methods which may be used in forming the compound ingot. For instance strips of sheet brass coated with a flux 60 of borax may be located in a mold as cores, and molten invar steel poured into the mold. The molten steel will melt a film of brass and when the ingot cools the brass will be fused to the walls 65 of the grooves in the steel. Another method is to take a slab of rolled invar, mill or die stamp longitudinal recesses in the slab to receive the brass, fill the recesses with a finely divided mixture of brass filings and borax, then melt said 70 brass with an ordinary illuminating gas or acetylene torch, then grind the brass, united to the steel, level with the top of the steel, and then reduce the compound slab by rolling as previously described. Still another method is to solder 75 strips of rolled brass into the recesses of the

rolled invar with silver solder and then reduce as before by rolling down the compound slab.

In all the descriptions thus far the invar steel is represented as the continuous metal and the brass is represented as the divided metal. However this arrangement may be reversed in most cases. I may fuse molten invar steel into grooves in a slab of brass or Monel metal by arc welding, preferably the atomic hydrogen type of arc welding, or strips of invar steel may be silver soldered into grooves in a brass slab. Fig. 5 represents this arrangement. It is to be understood that the term "recess" as used herein applies also to the recesses directly formed in one side of a thin sheet of metal by a die stamping operation directly forming spaced recesses or depressions in the opposite side of the sheet. A thin sheet of one metal so formed with a series of recesses at one side alternating with a series of recesses in its opposite side may have secured in each of said recesses a layer or section of a different metal to thereby produce bimetallic stock material generally similar in form to that shown in Fig. 1.

Ordinarily, an element constructed in accordance with the present invention and designed for carrying an electric current without much heating up, will have the metal of high electrical conductivity as the continuous metal and the metal of lower electric conductivity as the divided metal. This arrangement is shown in the sheet of stock Fig. 5. Conversely, where it is desired to utilize the heating effect of an electric current passing through the thermostatic element to operate same, the two metals are preferably arranged as in Fig. 1 or Fig. 4, that is, with the high resistance invar steel continuous and the low resistance brass divided so that the current is compelled to pass through alternate portions of high and low resistance. The heating effect of the current passing through the portion of invar 40 may then be utilized to operate the element.

Invar steel having a very low coefficient of heat expansion is the best metal now known to me for use as the low expansion metal however, in lieu of brass numerous other metals may be used 45 for the high expansion metal, especially where it is desirable to have a thermostatic element suitable for high temperatures. For instance Monel metal may be used with the invar steel, or another steel, one having a high percentage of 50 copper may be used with the invar steel to form the thermostatic element. A very good high expansion alloy for use with invar has the following composition, 12-15% nickel, 5-7% copper, 55 1.50-3% chromium, and the balance electrolytic iron.

All the methods of making the thermostatic stock thus far described, involve the insertion of one metal in grooves formed in a continuous sheet of the other metal, but in some cases, especially when the quantity of elements desired is small, it may be more economical to use a different procedure in making corrugated elements. For example, as shown in Fig. 4-A, a slab of 60 rolled invar may be permanently sandwiched between two slabs of rolled brass, the joint between adjacent surfaces being made with silver solder or other suitable means. After a compound slab is thus formed it is cold rolled down 65 parallel to its length to the desired thickness, and after the rolling operation, sections of the outer surfaces of brass are removed down to the steel. Then each surface will show alternate sections 70 of brass and invar. In the construction shown in Fig. 4-A as in those previously described, a 75

section showing brass on the upper surface will show invar on the lower surface and likewise a section showing steel on the upper surface will show brass on the under surface. The sheet of stock shown in Fig. 4—A may be corrugated as previously described.

In forming the stock shown in Fig. 4—A the sections of brass may be removed in several ways, for example, they may be removed mechanically by milling or grinding, or chemically, by covering the sections of brass that are to remain with an asphalt varnish, then dipping the sheet in a mixture of nitric acid and water having a specific gravity of 1.2. The acid will etch off the exposed sections of brass and leave remaining those sections of brass protected with varnish. The acid will not affect the steel. The brass sections may also be removed by electrolysis. In such case the sections of brass to remain are first protected with wax or shellac and then the sheet is placed as the anode in an electroplating solution. The brass stripped off will be deposited on some other object as the cathode. The electroplating solution is preferably 17½ parts copper acetate, 22 parts potassium cyanide, 17½ parts sodium bisulphide, 21½ parts sodium carbonate to 100 parts of water by weight. Two or more corrugated thermostatic elements expanding and contracting in the direction of their lengths may advantageously be combined into a single thermostatic element in some cases, one such combination being illustrated in Fig. 8. The element shown in Fig. 8 comprises two similar corrugated strip elements 11 and 12 each rigidly attached at one end to the corresponding end of the other through a connecting end portion 13. As shown in Fig. 8, the opposite end portions 11a and 12a of the strip sections extend alongside of one another in the direction of the element, and are apertured for attachment to a part 14 such as a valve, switch contact or the like to be actuated. With each section thus connected at its opposite ends to the corresponding ends of the other section, each section reinforces the other against lateral bending. Advantageously the two sections are similar not only in shape but in disposition in that each individual corrugation or curved portion of each section is alongside a similar corrugation or curved section of the other section, and preferably also the concave and convex sides of each corrugation or curved portion of one section faces in a direction opposite to that in which the concave and convex sides of the alongside corrugation or curved portion of the other section faces. So arranged each longitudinal portion of each section expands and contracts as does the alongside portion of the other section in response to a change in temperature which is advantageous in some cases, as for instance, when different longitudinal portions of the element are subjected to different temperatures.

The previous descriptive matter relates principally to a thermostatic element made by corrugating flat sheet stock. However the element may be constructed in the form of a deeply corrugated tube either seamless or with a welded joint. Fig. 9 shows a sheet of stock like that shown in Figs. 1 and 7 bent into the form of a tube with a welded longitudinal joint c—d, preferably formed by atomic hydrogen arc welding the abutting strip edges. After the tube is made it may be deeply corrugated, as shown in Fig. 10, by any of the methods now in use for forming thin walled deeply corrugated tubing. Fig. 11 shows a compound seamless tube composed of

three layers permanently joined together, the middle layer being invar and the two outer layers being brass. In making the tube shown in Fig. 11, a compound hollow ingot is first formed with the three layers joined together by fusion, and this ingot is cooled down to a thickness of wall suitable for corrugating and is then given the corrugated form as shown in Fig. 12. Sections of the brass represented by the dotted lines in Fig. 12 are removed either before or after the tubing has been deeply corrugated. The brass is removed either chemically or by electrolysis, in the same manner as described previously for removing sections of brass from the flat sheets. The deeply corrugated tubes shown in Figs. 10 and 12 will contract or expand longitudinally in response to a change in temperature.

Fig. 13 shows a thermostatic tube made up of a seamless tube of one metal like invar, recessed to receive segments of another metal like brass. The segments of brass are permanently joined to the invar, preferably by fusion, and then the walls of the compound tubing reduced by cold drawing to the desired thickness. The tubing shown in Fig. 13 will collapse approximately into the shape shown in Fig. 14, when heated and will again return to its original shape when cool.

Fig. 15 shows another variation of the corrugated thermostatic element, in which the corrugations are bulged outwardly at the center to make the element more rigid, so that it will stand out horizontally, even if made of very thin stock, when supported at only one end.

The thermostatic element strip 20a shown in Fig. 16 may be cut in the manner indicated in Fig. 16 from thermostatic stock sheet material like that shown in Fig. 7, and is characterized by the fact that the side edges of the strip are undulating with the concave and convex portions of one edge directly adjacent concave and convex portions respectively of the other edge, so that the width of the strip alternately increases and decreases along the length of the strip, and is further characterized by the fact that the meeting surface edges of the two metals of the strip are inclined to the length of the latter and are located in the narrow portions of the strip.

Fig. 18 shows a thermostatic element with shallow corrugations, and Figs. 19 and 20 a thermostatic element with deep corrugations formed from the strip 20a. In each of the last mentioned thermostatic elements the wider portions of the strips are at the crests of the corrugation curves and the surface joints between the metals having the different coefficients of expansion are located in the narrow neutral portions of the elements midway between adjacent oppositely facing crests. The narrowing of said portions, which are subjected to bending stresses by the relative expansion of the layers in the wider crest portions, gives increased sensitivity in response to temperature changes as compared with the elements previously described. The method of separating the strip 20a from the stock sheet material illustrated in Fig. 16 obviously avoids waste in forming a multiplicity of said strips from the same sheet.

Using the same stock shown in Fig. 16, a thermostatic element may also be made having helical corrugations therein and conforming in the form of its inner and outer surfaces to the surface of a segment of a helical worm. 20b represents a strip of stock cut out for this type of element. Fig. 21 is a front view of the helical corrugated element and Fig. 22 is a plan view of this

element. A helical corrugated element of this type can best be formed by using a worm and worm gear with the proper clearances as the forming dies.

5 Fig. 3 represents in section an electric heating device, such as an electric heating iron, having a heating element (1), and a quick opening and closing thermostatic switch (2), the element 1 being a resistor in an electric heating circuit including a source of current (10). The switch shown in Fig. 3 comprises a corrugated thermostatic element 2a anchored at one end and carrying a switch contact 5 at its free end, and a co-operating switch contact 4 carried at the free end 15 of a screw 7 threaded into a supporting anchorage adjacent the anchorage end of the element 2a. The latter is formed adjacent its free end with a spring tongue or latch part 3 cooperating with spaced apart latched recesses formed in the 20 insulator 8 which is carried by the screw 7 and carries the contact 4 in Fig. 3. When the temperature of the surrounding atmosphere drops to a predetermined point the corrugated thermostatic element 2a contracts and the latch 3 deflects out of one of said latch recesses into the other causing a snap contact between contacts 25 (4) and (5) and thus completing the circuit. As the surrounding temperature becomes too high the thermostatic element again tends to expand longitudinally. The force exerted on latch (3) by the expanding element 2a causes the latch to deflect back into the latch recess initially occupied and contact between (4) and (5) will be broken with a snap action. The arrangement of the partly cut out thermostatic section (6) of the element 30 2a is such that it will tend to hold the contact tight until broken with a snap and likewise section (6) tends to prevent the contact from taking place until it can do so with a snap action. The 35 thermostatic switch can be set for any desired operating temperature by adjusting screw (7). (9) is an electric insulator.

Having described my invention what I claim and desire to secure by Letters Patent is:—

45 1. A corrugated bimetallic thermostatic element of uniform thickness comprising a continuous sheet of one metal having recesses therein, and another metal permanently imbedded in and filling said recesses and having a coefficient of expansion different from that of the first mentioned metal.

50 2. A thermostatic element of uniform thickness comprising a continuous piece of recessed metal and inserts of another metal permanently united to the walls of and completely filling the recesses in said first mentioned metal, the two metals having different coefficients of expansion.

55 3. A thermostatic element comprising a rolled sheet of uniform thickness including a continuous web of one metal alternately recessed at opposite sides of the sheet and sections of another metal, said metals having different coefficients of expansion, filling said recesses and integrally connected to the said web.

60 4. A thermostatic element comprising a rolled sheet of uniform thickness including a continuous web of one metal alternately recessed at opposite sides of the sheet and sections of another metal, said metals having different coefficients of expansion, filling said recesses and integrally connected to the said web, said sheet being bent into a structural form the shape of which is distorted in a predetermined manner by the unequal expansion of the different metals on changes in the 65 temperature thereof.

5 5. A thermostatic element comprising a rolled sheet of uniform thickness including a continuous web of one metal alternately recessed at opposite sides of the sheet and sections of another metal, said metals having different coefficients of expansion, filling said recesses and integrally connected to the said web, said sheet being formed with alternate bends with one metal exposed at the convex side and the other metal exposed at the concave side of each bend.

10 6. A corrugated bimetallic thermostatic element consisting of sheet material of uniform thickness including a number of similar and similarly proportioned corrugation loop portions extending in one direction and alternating with an equal number of loop portions similar in number and proportions to the first mentioned portions and extending in the opposite direction, each of said loops comprising an inner layer of metal having one coefficient of expansion and an outer layer of another metal having a different coefficient of expansion.

15 7. A bimetallic thermostatic element in the form of a strip of corrugated sheet material the corrugation loops of which comprise an inner layer of metal having one coefficient of expansion and an outer layer of another metal having a different coefficient of expansion, the sheet material being curved transversely to the length of the element to increase its transverse stiffness.

20 8. A bimetallic thermostatic element in the form of a strip of corrugated sheet material the corrugation loops of which comprise an inner layer of metal having one coefficient of expansion and an outer layer of another metal having a different coefficient of expansion, the loop crest portions of said strip being wider than the intervening portions of the strip.

25 9. A bimetallic thermostatic element in the form of a corrugated strip of sheet material comprising integrally connected sections of metals having different coefficients of expansion so arranged that exposed portions of one metal alternate with exposed portions of the other metal at each side of the sheet and each of said portions 30 exposed at one side of the sheet is in juxtaposed relation with a portion of different metal exposed at the other side of the sheet with the meeting edges of the adjacent portions exposed at each side of the sheet inclined to the length of the strip 35 and included in the strip portions which connect oppositely extending corrugation loops.

40 10. A thermostatic element comprising two similar side by side strip sections each rigidly connected at each end to the corresponding end of the other and each including one or more curved portions alongside a corresponding curved portion of the other section, the concave and convex sides of each such curved portion facing in directions opposite to those respectively faced by the 45 concave and convex sides of the adjacent curved portion of the other section, each such curved portion comprising a layer of one metal at one side and an integrally connected layer of a different metal at its opposite sides, one of said layers 50 having end portions extending beyond the ends of the other layer and layer portions of the same metal as the last mentioned layer integrally connected to said end portions at the sides of the latter remote from the last mentioned layers, said 55 metals having different coefficients of expansion whereby a change in the temperature of the element causes the two ends of each section to move 60 toward or away from one another.

65 11. A thermostatic element comprising two 70

similar side by side strip sections each rigidly connected at one end to the corresponding end of the other and each including one or more curved portions alongside a corresponding curved portion of the other section, each such curved portion comprising a layer of one metal at one side and an integrally connected layer of a different metal at its opposite sides, one of said layers having end portions extending beyond the ends of the other layer, and layer portions of the same metal as the last mentioned layer integrally connected to said end portions at the sides of the latter remote from the last mentioned layer, said metals having different coefficients of expansion where-
by a change in the temperature of the element causes the two ends of each section to move toward or away from one another.

12. A thermostatic element comprising an extended body comprising rigidly connected portions of materials having different coefficients of expansion compressed into a thin sheet curved and having smooth surfaces without joint cracks and with a series of portions exposed at each surface and with the materials of each portion so ex-

posed having a different coefficient of expansion from that of the material of an adjacent portion, and with the material of each portion exposed at one surface having a different coefficient of expansion from the material in the juxtaposed portion exposed at the other surface.

13. A thermostatic element formed from a body comprising integrally connected portions of metal having different coefficients of expansion and adapted to be tempered by working operations, and compressed to reduce the thickness of said body and convert it into a thin sheet having smooth side surfaces at each of which is exposed a series of portions of metal so disposed that the metal of each portion exposed at each side of the sheet has a different coefficient of expansion from that of the metal of an adjacent portion exposed at the same side of the sheet and so that the metal of each portion exposed at one side of the sheet has a different coefficient of expansion from that of the metal of the juxtaposed portion exposed at the opposite side of the sheet.

NORMAN L. DERBY.
